SPRING ACTUATED SASH BALANCE

Angelo Colonna, Philadelphia, Pa.

Application November 26, 1951, Serial No. 258,167

3 Claims. (Cl. 16—200)

1

The present invention relates to a structure which is characterized by a stationary support or frame structure, and a closure, such as a sash, slidably mounted in said frame structure and has more particular reference to a novelly constructed and improved closure balancing and retaining device.

The principal object of the invention is, of course, to dispense with sash cords and weights and friction-type sash holders and retainers and to employ in lieu thereof a spring activated balance which is interposed between the lower frame member or other closure and the underlying stool or equivalent portion of the stationary frame structure.

Another object of the invention is to structurally, functionally and otherwise improve upon similarly performing and constructed prior art spring controlled sliding closure balances by providing one which is highly simple, practical and unusually efficient in operation, the great advantage being that the sash will be balanced at any point desired by the operator and will be allowed to readily move to open or closed positions with the greatest of ease and satisfaction.

Considered from a more specific structural point of view the improved device has to do with a stationary support structure having opening means, a closure for said opening means slidably mounted in said support structure, vertically disposed levers pivoted on said support structure and disposed in crossed relation, the upper ends of said levers being free, movable toward and from each other while retaining coplanar relationship and having free and movable end thrust contact with a cooperating lower portion of said closure, spring balance units fixed on said support structure, and connection means between the respective lower means of said levers and their respective spring balance units.

A further object of the invention is to provide the upper end of the levers with antifriction free turning rollers, the latter being properly operable in the channel portion of a guide track which is channel-shaped in cross-section and properly secured to the lower rail or frame member of the sash or other closure.

Then, too, novelty is predicated on the adoption and use of lever means characterized by first and second levers disposed in spaced parallelism, a third lever operating in the space between the first and second levers, all of said levers being substantially L-shaped in general configuration, having their lower ends pivoted on a common base or foundation plate and offset and converg-

2

ing toward each other and pivotally connected with coacting plungers which operate in spring loaded cylinders, the cylinders being in spaced axial alignment and fixed on the support structure.

Other objects and advantages will become more readily apparent from the following description and the accompanying sheets of illustrative drawings.

10 In the accompanying drawings, wherein like numerals are employed to designate like parts throughout the views:

Figure 1 is a view which is primarily in elevation with portions fragmentarily shown and appearing in section showing the complete sash balance and the manner in which it is constructed and utilized to support the sash in an elevated position.

Figure 2 is a view similar to Figure 1 showing 20 the sash lowered to open position and showing the manner in which the levers and other parts function at this stage of operation.

Figure 3 is an enlarged view primarily in edge elevation showing the sash balance device of Figure 1 and observing the same in a direction from 25 right to left.

Figures 4 and 5 are enlarged sections taken on the planes of the lines 4—4 and 5—5 respectively of Figure 1, looking in the directions of the arrows.

Figure 6 is an enlarged view of one of the spring units with parts shown in elevation and section.

Figures 7 and 8 are enlarged fragmentary elevational views of the lever actuated end of the 35 respective reciprocable plungers.

With reference to Figure 1 the numeral 10 denotes what may be broadly referred to as relatively stationary support structure and which is characterized by a frame construction 12 and a sliding sash 14 having a frame including a bottom rail 16 and a center horizontal rail 18 which constitutes a convenient operating handle for the sash. The expression "sash" is used to designate any sliding closure such as a panel, door or the like.

40 The lower frame member 16 is provided with a guide track 20 which is channel shaped in cross-section and has its bight or web 22 secured at 24 to said frame member 16. The rear flange is denoted by the numeral 26 and this is wider or deeper than the narrow front flange 28.

45 The lever means is made up of three substantially duplicate levers. The arrangement to the right in the drawings comprises a pair of duplicate first and second levers 30 and 32 (see Figure 5) and the remaining single lever to the left

is denoted by the numeral 34 in Figure 4. The lever 34 works in the space between the spaced parallel levers 30 and 32 so that when in the position seen in Figure 1 the linearly straight portions are in crossed relationship. It will be observed in this figure in particular, that the levers are substantially L-shaped in general form. The obtuse angled lower end portions of the levers, denoted at 36 and 38 in Figure 1, are disposed in converging relationship and are pivotally mounted on a common foundation plate 40 which is fixedly supported. In this connection and in reference to Figure 4 there is a pivot bolt 42 screwed into the plate 40 and provided with suitable spacing washers 44 and 46. Similarly, the first and second levers 30 and 32 are mounted on a pivot bolt 48 screwed into the plate 40 and provided with suitable spacing washers or collars 50, 52 and 54 respectively.

There are two spring balanced units and they are substantially duplicates in construction and it is believed that, for convenience, the like parts in the respective units may be designated by corresponding or like reference numerals. To this end each unit comprises a horizontally disposed cylinder 56 having a coil spring 58 mounted therein. The reciprocable plunger 60 is slideable in the cylinder and has one end bearing against the coacting end of the coil spring. The plunger to the left is provided as best shown in Figure 4 with a pair of ears 62-62 while the opposite plunger to the right is provided with a single ear 64. Each ear is provided with an elongated linking slot 66 as shown for example in Figure 6. Under this arrangement the converging lateral end portions 36 and 38 of the respective levers are pivotally connected as at 68-68 to their respective slotted ears or lugs, 62-62 on the one hand and 64 on the other hand. This provides the desired self-adapting pivotal connections between the respective plungers and their respective levers. Each cylinder is mounted in place partly by a flat attachment plate 70 and a complementary angle plate 72, the vertical flange of the plate 72 being superimposed against and attached to the plate 70 and the horizontal flange resting atop the cylinders and both parts 70 and 72 being welded or otherwise joined with the coacting cylinders. The upper end portions of the respective levers are provided with laterally offset members 74 providing suitable mountings for the idling anti-friction rollers 76 and 78 respectively. The rollers are shown in the form of sheaves but may be of any appropriate construction. They are also shown traveling between the flanges 26 and 28 of the guide track 20 while in rolling contact with the web 22. Therefore the roller equipped ends of the several levers move toward and from each other against the tension of the respective coil springs in the respective cylinders and they travel in the same plane. It will therefore be clear that when the sash or other closure 14 is in the position shown in Figure 1 the levers are substantially vertical with their linearly straight portions in crossed relationship, the rollers being in confined rolling contact in the guide tracks 20. The lower end portions 38 are in converging relationship and are so linked with the plungers that the plungers operate toward and from each other in axial alignment. The springs are so balanced that they cushion the action of the plungers with the precision required. With this construction and arrangement the sash may

be opened and closed by hand and will, obviously, stay in the position in which it is placed without the aid of extraneous fixtures, brackets, clips or other friction type retainers (not shown).

Minor changes in shape, size, materials and rearrangement of parts may be resorted to in actual practice provided no departure is made from the invention as claimed.

Having described the invention, what is claimed as new is:

1. A sliding closure balance assembly for use in connection with a stationary support structure having opening means and a closure for said opening means slidably mounted in said support structure; comprising vertically disposed levers adapted to be pivoted on said support structure and disposed in crossed relation, the upper ends of said levers being free and, movable toward and from each other in coplanar relationship and adapted to have free and movable end thrust contact with a cooperating lower portion of the stated closure, spring balance units adapted to be fixed on said support structure, operating means affording an operating connection between the respective lower ends of said levers and their respective spring balance units, there being two spring balance units, the latter being in spaced axial alignment with each other and each unit embodying a cylinder, a coil spring in said cylinder, and a plunger slideable in said cylinder in end thrust contact with said spring.

2. A sliding closure balance assembly comprising a horizontal guide track adapted to be attached to and carried by a lower portion of a closure, said track being channel-shaped in cross-section and being open at opposite ends, a pair of cylinders adapted to be fixedly mounted on support structure therefor in axial alignment with each other and with inner adjacent ends spaced apart, a foundation plate adapted to be fixedly mounted on said support structure in close proximity to the space existing between the inner ends of said cylinders and situated on a plane parallel to but out of axial alignment with said cylinders, spring pressed plungers slideable in said cylinders, vertically disposed levers having portions disposed in crossed relation, said levers having upper ends provided with anti-friction rollers confined for operation in the channel of said track, the lower ends of said levers having obtuse angular portions superimposed on and pivoted to said foundation plate and said end portions being disposed in converging relation and pivotally connected to corresponding inner ends of their respective cooperating plungers.

3. In a sash balance assembly adapted for use in connection with a sliding closure operating in a frame, a pair of cylinders adapted to be fixed on a stationary support structure in axial alignment with each other, a spring in each cylinder, a plunger sliding in each cylinder in operating relation with its spring, a foundation plate adapted to be fixed on said support structure in a space between inner adjacent ends of said cylinders, first and second duplicate spaced parallel levers, a third lever operating in the space between said first and second levers, all of said levers being substantially L-shaped and having their lower end portions pivotally mounted on said foundation plate and pivotally connected at said lower end portions with their respective plungers, rollers mounted for idling on the opposite ends of said levers, and a separate open ended guide track channel-shaped in cross-section

adapted to be mounted on a sliding closure, said rollers operating in the channel of said track.

ANGELO COLONNA.
